UNITED STATES PATENT OFFICE.

FRED SCHMIDT, OF CHICAGO, ILLINOIS, ASSIGNOR OF ONE-FOURTH TO EDWARD L. GIRARD AND ONE-FOURTH TO MICHAEL A. MESSLEIN, BOTH OF CHICAGO, ILLINOIS.

INTERNAL-COMBUSTION ENGINE.

1,331,281.

Specification of Letters Patent. Patented Feb. 17, 1920.

Application filed August 15, 1919. Serial No. 317,682.

To all whom it may concern:

Be it known that I, FRED SCHMIDT, residing at Chicago, in the county of Cook and State of Illinois, have invented certain new and useful Improvements in Internal-Combustion Engines, of which the following is a specification.

The invention relates to improvements in internal combustion engines and has especial reference to engines of the rotary type.

One of the objects of the invention is, generally, to improve engines, to increase smoothness of operation; enhance their efficiency; to simplify their construction and to reduce cost of production.

One of the specific objects is to compress the power charge outside of the combustion chamber and to entirely shut off the combustion chamber from the chamber within which the charge is compressed, so that the burned products of combustion cannot be caused to mingle with the gases of a subsequent charge being compressed, as usual with engines within which the combustion chamber and the charge compressing chamber is the same chamber.

Another object is to provide an engine in which the rotary power-producing element is provided with a large number of peripheral abutments against which the burning charge impinges to produce continuing power impacts, by the force of the burning charges, projected from one or more of the combustion chambers associated with the rotary element, whereby the momentum of the mobile burning charge is available as a power producing factor.

Other, further and more specific objects of the invention will become readily apparent, to persons skilled in the art, from a consideration of the following description when taken in conjunction with the drawings, wherein:

Figure 1 is an end elevation of a plural unit engine embodying the invention.

Fig. 2 is a plan view of the engine.

Fig. 3 is a section, taken on line 3—3 of Fig. 1.

Fig. 4 is a section taken on line 4—4 of Fig. 3 showing one group of elements of one unit of the engine, in cross section, or, in other words, showing one engine, in the multiple of four, depicted by the drawings.

Fig. 5 is an elevation of the end of the

engine structure, opposite to that shown in Fig. 1.

Fig. 6 is a central section through the group of charge compressing cylinders.

Fig. 7 is a section taken on line 7—7 of Fig. 3.

Fig. 8 is a section taken on line 8—8 of Fig. 7.

Fig. 9 is an isometric perspective view of the slide valve that controls communication between the combustion chamber and the rotor of one unit or group of engine elements.

Fig. 10 is an enlarged section taken on line 10—10 of Fig. 1.

Fig. 11 is a section taken on line 11—11 of Fig. 10.

Fig. 12 is a section taken on line 12—12 of Fig. 10.

Fig. 13 is a section taken on line 13—13 of Fig. 6.

Fig. 14 is a fragment of the rotary piston or rotor common to all of the engine units.

Fig. 15 is a section taken on line 15—15 of Fig. 1.

In all the views the same reference characters are employed to indicate similar parts.

In the embodiment of the invention, as depicted in the present drawings, 20 is the housing, consisting of flat side rings 21 and 22 and an end peripheral wall 23. The housing is fixed to a stationary part 24 which may be provided with any sort of a base suitable for the particular construction. A rotor 25 is provided with a hub 26, secured to the power shaft 27 by a key 28. The shaft 27 has bearings in the hubs 24 and 29 that are parts of the flat rings or plates 21 and 22. The peripheral surface of the rotor 25, carries a ring 30 from which radially project a series of pyramid-shaped abutments 31, in staggered relation. The ring 30 is fixed to the rotor in a suitable manner and is held in position by a flat ring 32 and a series of screws 33. The charge that produces the power of the engine by its force or impact, impinges against the surfaces of the numerous pyramids, during the rotative cycle of the rotor. The pyramids are staggered so that at all times there will be a certain number of the pyramids in the most advantageous place to receive the maximum effect of the projected charge. An inner wall 34, of the annular housing,

has its inner surface in very close proximity to the outer pointed ends of the pyramids 31.

Located at suitable distances around the structure 20 are combustion chambers 35; in the present exemplification there are four such chambers, one only, however, will be described, as the chambers are all alike in every essential respect.

A port 36, is made in the ring 34, which 10 communicates with the combustion chamber 35 through a rotatable reversing valve 37. The port 36, and the port 37' of the valve 37, are in tangential alinement when communication is established between the combustion chamber 35 and the rotatable piston or rotor 25. A spark plug 38 is employed to explode the charge within the chamber 35. Another port 39, similar to the port 36 but inclined in the opposite direction from a radial line, 15 is adapted to be used when it is desirable to rotate the rotor in the opposite direction. In which event the port 37', of the valve 37, is brought into alinement with the port 39, whereupon the energy of the exploding 20 charge will be directed tangentially upon the rotor, as in the former case, in the same manner, but in the opposite direction.

Between the ring 34 and the combustion chamber is a curved sliding valve 40, having 30 oppositely inclined ports 41 and 41'. It is this valve that is used to complete communication between the combustion chamber 35 and the rotor, during the cyclic operation of the engine, while the valve 37 is used only 35 when it is desirable to reverse the direction of motion of the rotor.

When direction of motion of the rotor is to be changed the valves 37, of each of the engines, must be simultaneously oscillated to 40 the same extent and for this purpose I provide a ring 42, journaled on the hub 24 and provided with a handle 43. Projecting from the ring is, also, an index 44, movable over a dial 45, to indicate to the observer the 45 direction in which the engine is being rotated. Connected to the ring in spaced apart relation are a series of slotted-links 45, each of which is secured to a valve 37. Each of the links is pivoted to the ring, as at 46. 50 Now it will be manifest that when the handle 43 is moved to the left, as shown in Fig. 5, the valves 37 will have their ports 37' in register with the ports 39, in the ring 34, thereby causing communication from the 55 combustion chamber 35 to pass through the ports 41', and causing the rotor to be revolved in the direction opposite to that shown in Fig. 4, or in clockwise direction, whereas as shown in Fig. 4 the rotor would 60 be moved in anti-clockwise direction.

Assuming that an explosion has occurred in the combustion chamber 35, see Fig. 4, the force of the explosion will cause the projected gases to pass through the port 37', of 65 the valve 37, through the port 41 of the

valve 34, and forcibly impinge upon the presented surfaces of the pyramidal abutments 31, thus projecting a charge against these presented surfaces in tangential direction with such force and effect as to cause an 70 impulse of movement of the rotor. After the gases have passed along the surface of the rotor to a point 47, they are exhausted through radially exposed tubes, or pipes 48. The exhaust may thereafter be conveyed to 75 any suitable point remote from the engine by connecting a conduit to these tubes. It is, of course, understood that the exploded charges will be periodical and that they will occur in sequential order, in the several 80 engine units presented to the rotor as in other forms of engines. The result, however, is that each cylinder may be made to produce a power impulse at each reoccurring revolution of the rotor, and in the embodiment of 85 the drawings there would be four power impulses during each revolution of the rotor.

Before explaining the operation of the valve 40, it may be well to indicate the manner in which the charge is compressed and 90 forced into the combustion chambers 35, and there exploded. Each of the engine units is provided with a cylinder 50, within which reciprocates a piston 51. Into these cylinders 95 the charges are drawn and compressed, and then at the end of the compression stroke they are passed through a port 52, and preferably a check valve 53, into the, respective, combustion chamber 35. The cylinders 50 are preferably hollow and a conduit containing the valve 53 is open at the upper end of the piston, as at 54, and communicates with a port 55 in the side wall of the cylinder facing toward the combustion chamber. The valve 53 opens toward the compression chamber 56 100 from pressure within the cylinder 50, but it prevents back pressure from the combustion chamber into the compression chamber, and also prevents the gases of combustion from mixing, or mingling with the fresh gases 105 drawn into the compression chamber, at the time the explosion is made in the combustion chamber. During the outstroke of the piston 51, shown in Fig. 10, the valve 57 is 110 opened and a charge is drawn into the compression chamber 56, the port 53' of the conduit. A port 58 extends down the inside of the cylinder in its side wall, so that the port 55 may be in communication therewith.

The piston 51 may be oscillated on its rod 120 so as to bring the port 55 out of line with the port 58, as clearly shown in Fig. 10, by a pin 60 which is secured in one side of the piston, as at 61. The free end of the pin 60 projects into a cam way slot 62, in a stationary cam 63. The cam is provided by an outer wall 64 and a spaced apart inner wall 65 with a groove or camway 62 between the two walls. The pin 60 has its inner end 125 constantly within the camway, or groove 62, 130

and when the piston 51 is reciprocated in the cylinder 50 at the end of its instroke, the pin 60 passes from the slot on the left hand side to the slot on the right hand side, or 5 on the opposite side of the wall 65, thereby oscillating the cylinder on its rod and bringing the port 55 out of register with the port 58 at the proper time in the cycle of operation so that the port 55 will no longer communicate, through the port 58 or directly, 10 with the conduit 42. The piston rod 70, is connected to the piston 51 in such manner, as at 71, whereby the piston may be oscillated or rotated independently of the rod. 15 The pin 60 not only oscillates the cylinder 50, by its passage through the cam 63, but it moves the valve 40 in proper sequential order.

The valve 40 is provided with notches 73 20 on its sides within which extends arms 74, which are secured to an oscillatable shaft or pin 75. The pin 75 extends through the plate, or ring 22, and has secured thereto on its outer end an arm 76. The outer end of 25 the arm 76 carries a pin 77 that extends into a slot 78 of one member of the bell crank lever 79. The arm 80, of the bell crank lever, is secured to the arm 81 and moves therewith. The end of the arm 81 extends 30 over the camway 62 in the path of the pin 60, so that when the pin 60 passes down through the cam channel 62 on the right hand side, as viewed in Fig. 7, it displaces the arm 81 of the bell crank lever 79, thereby 35 moving the arm 76, and the arm 76, being connected to the pin 75, the arms 74 are moved thereby and therefore, inasmuch as they are inserted in the notches 73 in the valve plate 40, the valve is moved a sufficient 40 distance in the cycle in proper timed relation with the movement of the piston. A latch lever 83 is pivoted, as at 84, and is held in position against the stop 85 by spring 86. The end 87 of the latch lever extends into 45 the path of the pin 60 when it is moving in clockwise direction in the cam groove 62, and prevents the pin 60 from returning in the direction from which it came. A spring 87 is connected to the arm 80, of the bell crank lever, and normally holds the valve 40 in closed position, or while the pin is 50 traveling through the camway 62, after it leaves contact with the arm 81 of the bell crank lever 79.

55 The charges subsequently to be burned in the respective combustion chambers, are compressed by the axially moving pistons 51 in the cylinders 50. They are moved in consecutive order by a mechanism which will 60 now be described.

65 Mounted on the shaft 27, and rotatively secured thereto, is a gear wheel 90 in mesh with another gear wheel 91 mounted upon a pin or shaft 92 supported upon the frame or housing and secured to the flat rings 21 and

22. On the opposite end of the pin or shaft 22 is crank arm 93, secured thereto by a pin 94 or otherwise. A plate 94 is secured to the housing, as by pins or bolts 195. The piston rod 70 is continuous and connects the piston 70 51 to the piston 51^b diametrically opposite, while the piston rod 70' connects the pistons 51^a and 51^b in the same manner. The plate 94 is slotted with two crossing slots 95 and 75 96. These slots are in axial alinement with the respective piston rods 70 and 70'. The piston rod 70' is located back of the plate 94 and a sliding guide member 98, is connected to the rod 70', as by a screw 99 and is 80 slidable in the groove 96, while a similar slip plate 100 slides in the groove 95, and is connected to the piston rod 70 by a similar means. The distance of the movement of the clip 98 is limited by a slot 101, which permits the clip to move sufficiently for the 85 purpose intended.

The crank arm 93, on the shaft 92, is connected by a link 102, to another link 103, as at 104, and the link 103 is pivotally connected to the clips 98 and 100, as clearly 90 shown in Fig. 6.

Now it is manifest that when the crank arm 93 is rotated in anti-clockwise direction, it will move the link 102 to dotted line position, shown in Fig. 6, whereupon the piston rod 70 will be moved to the left causing the piston 51^b to move inwardly of the cylinder 50^a and the piston 51^a to be moved out into dotted line position during the outstroke. At the same time it will cause the piston 51^b to be 95 moved on its instroke and the piston 51 to be moved on its outstroke, all of which is shown in dotted lines in said figure. When the crank passes its center these movements will then be reversed. While the pistons are moving 100 on the outstroke, the inlet valve 57 of each of the cylinders, will be opened and the suction produced by the outstroke of the pistons will cause the cylinders to fill with an explosive mixture. The next cycle in the operation 105 of the pistons will be to compress the mixture and about the same time the valve 40 is moved, and coincidentally a spark is made by the spark plug 38 in the combustion chamber 35 and thereupon the hot gases of 110 combustion will be violently expelled from the combustion chamber and will impinge upon the irregular surfaces forming the abutments on the rotor 25, causing a power impulse to be imparted to the rotor. 115

The inlet valve 57 is carried by a stem 105 which guides the valve which is yieldingly held in closed position, by means of a spring 106, that bears upon the head 107, at the upper end of the valve stem 105, and bears 120 at the other end upon the upper end of the cylinder. A bell crank arm 108 has one of its ends 109, bearing upon the head 107 and its other arm 110 pivotally connected, as at 111, to a downwardly extending valve oper- 130

ating arm 112. The arm 112 terminates at 113 and for a part of its length is in the path of the pin 60, that travels in the camway 62, so that when the pin 60 is moving down-
 5 wardly in the camway 62, the lower end of the arm 112 is moved to the right and being pivoted, as at 114, it moves the vertical arm 110, of the bell crank to the left, thereby depressing the valve 57 by impingement of
 10 the arm 109 upon the head 107. The valve 57 is therefore caused to remain open until the pin 60 passes out of contact with the lower end 113 of the arm 112 or during the inspiration stroke and the piston is about to
 15 return on its compression stroke. The movement of the valve 57, therefore, is made in timed relation with the piston within the cylinder, which directly controls the valve.

A fuel manifold 120 is common to all of
 20 the cylinders and is connected thereto, as by branch pipes 121. A pipe 122 is connected to a suitable source of fuel supply.

Now it will be manifest that to start the engine it is only necessary to primarily rotate the shaft 27 when the pistons 51 on their out strokes will draw into the cylinders 50 the charges of gas to be compressed and further rotation of the shaft 27 will cause compression of the gas in the cylinders, in sequence, and combustion in the cylinders in proper turn to produce the power impulses necessary to rotate the shaft 27 by the power of the explosions, as in engines of other types.

35 While there is herein shown a single embodiment of the invention for the purpose of clear disclosure it will be manifest, to persons skilled in the art, that considerable change in the configuration and disposition 40 of the parts is permissible within the spirit and scope of the appended claims.

Having described my invention, what I claim is:—

1. A rotary gas engine having in combinative association, a cylinder, and a reciprocating piston therein to form and compress a charge of fluid fuel; a combustion chamber into which the fuel under compression is conducted at the end of the compression 50 stroke of the piston; a valve operated in timed relation, with the piston, to control the conduit between the cylinder and the combustion chamber; a rotor, provided with a plurality of projections, or abutments 55 against which the burning charge is tangentially projected; a valve having a port inclined substantially tangential to the periphery of the rotor and connecting the space surrounding the rotor with said combustion chamber, and means, in the combustion 60 chamber, to ignite the charge.

2. A rotary gas engine having in combinative association, a plurality of cylinders and reciprocating pistons therein to form and 65 compress a charge of fluid fuel in each cyl-

inder in cyclic order; a combustion chamber for each cylinder into which the fuel under pressure is conducted at the end of the compression stroke of the respective pistons; a valve, for each engine, operated in timed relation with its piston to control the conduit between the cylinder and combustion chamber; a rotor, common to all of the cylinders provided with a plurality of peripheral abutments against which the burning charge 70 from each of the cylinders is tangentially projected; a valve for each combustion chamber, having a port inclined substantially tangential to the periphery of the rotor and connecting the space surrounding 75 the rotor with the respective combustion chamber and means, in the combustion chambers to ignite the charges in regular order.

3. A rotary gas engine having in combinative association, a rotor; a housing within which said rotor is rotatable; a series of radially extending abutments on the periphery of the said rotor; a series of combustion chambers, spaced apart, in said housing, radially beyond said rotor; a plurality of cylinders secured to said housing; a plurality of pairs of diametrically opposite connected pistons; means operable by the rotor for moving the pistons in timed relation in regular order and means operated by each piston to connect its cylinder to the combustion chamber at the end of its compression stroke. 95

4. A rotary gas engine having in combinative association a plurality of cylinders 100 and reciprocating piston therein each to form and compress a charge of fluid fuel in regular order; a combustion chamber for each cylinder into which the fuel under pressure is conducted at the end of the compression stroke of the respective pistons; a valve for each engine unit operated in timed relation with its piston to control the conduit between the cylinder and combustion chamber; a rotor common to all of the cylinders, provided with a plurality of peripheral abutments against which the burning charges from each of the cylinders is tangentially projected; a valve, for each combustion chamber, having two ports inclined in 110 opposite directions, each port substantially tangential to the periphery of the rotor and connecting the space surrounding the rotor with the respective combustion chamber; means to move the valve to direct the charge 115 through either port to reverse direction of rotation of said rotor and means, in each combustion chamber, to ignite the charge of fuel in regular order in harmony with the movements of the piston. 120

5. In a gas engine, two pairs of oppositely disposed cylinders; pistons in said cylinders; a connecting rod connecting together opposite pistons, said connecting rods being located at substantial right angles to each 130

other; a plate, having guides for each rod; a link pivotally connecting said guides together and having an extended end; a crank rotated by the rotor; a link connecting the said crank to the extended end of the first mentioned link whereby to move the pistons axially in sequential order; a rotor having a plurality of radially extending abutments on its periphery, common to all of the cylinders; a combustion chamber for each cylinder, and a valve, operated by the axial movement of each piston to connect its cylinder to its combustion chamber and means to explode the charge in the combustion chamber in timed relation.

6. A gas engine having a cylinder with a compression chamber at one end thereof; a piston in said cylinder to compress a charge of gas in the compression chamber; a combustion chamber; a valve to admit a fuel charge into the compression chamber to be compressed by the piston; a rotor; a valve between the rotor and combustion chamber and means, operated by the piston, to close the latter valve and to open the former valve during the inspiration stroke of the piston.

In testimony whereof I hereunto subscribe my name.

FRED SCHMIDT.
